UNITED STATES PATENT OFFICE.

WILLIAM J. DEMPSEY, OF SAN FRANCISCO, CALIFORNIA.

GARTER CLASP.

1,402,403.

Specification of Letters Patent.

Patented Jan. 3, 1922.

Application filed April 12, 1920, Serial No. 373,029. Renewed November 9, 1921. Serial No. 514,122.

To all whom it may concern:

Be it known that I, WILLIAM J. DEMPSEY, a citizen of the United States, residing at the city and county of San Francisco and 5 State of California, have invented new and useful Improvements in Garter Clasps, of which the following is a specification.

This invention relates to certain new and useful improvements in garment supporting 10 devices and especially to a hose supporting clasp by which the stocking may be securely held by the clasp without causing any stretching or appreciable wear on the portion of the hose which is engaged by the 15 clasp.

The invention relates further to a clasp which is readily and quickly applied or detached and which is adapted to grip a greater portion of the stocking than most 20 forms of garter clasps now in use, thereby reducing the tendency to cutting threads or tearing the stocking and forming stocking runners.

Further objects will hereinafter appear.

25 The invention consists of the parts and the construction, combination and arrangement of parts as hereinafter more fully described and claimed, having reference to the accompanying drawings, in which—

30 Fig. 1 is a perspective view of the garter clasp showing it applied to a stocking.

Fig. 2 is a section of the clasp showing the parts in interlocked position.

35 Fig. 3 is a view similar to Figure 2, but showing the clasp sections in position to be separated.

Referring to the drawings in detail, it will be seen that the garter clasp consists of two plate-like members as indicated at 40 2 and 3. These plate members are comparatively wide and the plate 2 terminates in a hook shaped member 4, while the plate 3 terminates in the head member 5. The upper ends of the plates are slotted as at 6 and both plates are attached to individual 45 straps which in turn may be supported as desired.

The main purpose of the present invention is to provide a garter clasp which will 50 present a wide grip and which is readily and quickly applied or detached. If it is desired to apply the clasp, it is first necessary to separate the clasp sections and to insert the edge of the stocking in the hook 55 section 4 of the plate 2, as shown in Fig. 2, and then to insert the head member as shown

in Fig. 3, which secures the fabric material of the stocking in the hook portion of the plate 2, when the plate 3 is turned into the position shown in Fig. 2. The plate 3 60 and the head member carried thereby when in this position clamps the stocking between the hook and the head portion and will therefore rigidly secure the same against removal. When it is desired to release the 65 stocking, it is only necessary to swing the plate 3 into the position shown in Fig. 3, and to separate the plates by removing plate 3 in the direction of arrow A, that is, the space between the main portion of the plate 70 2 and the upper lip of the hook 4 is such that the head member 5 can pass between the same. A complete release of the stocking is in this manner obtained and the hook can therefore be disengaged with relation to the 75 same. The clasp here shown presents a wide grip and therefore engages a comparatively large section or area of the stocking. The strain applied thereto is thus transferred to a comparatively large area and 80 wear and tear is proportionately reduced. Runners and tears are thus practically eliminated, and the life of the stocking should proportionately be increased.

The clasp sections are here shown as constructed of metal. They may be covered with a fabric material if desired and variations in the design may be resorted to. The materials and finish of the parts may otherwise be such as the experience and judgment 90 of the manufacturer may dictate.

The straps supporting the clasp sections 2 and 3 may be supported in any suitable manner. For instance, they may be attached by means of an elastic to a corset, or they may 95 be employed in connection with any other suitable harness or support.

The entire invention resides in the construction of the clasp members and I therefore do not wish to limit the invention to 100 any particular supporting means.

Having thus described my invention, what I claim and desire to secure by Letters Patent is—

1. A garter clasp comprising a pair of 105 plate members of suitable width, one of said plate members terminating in a hook, a head member formed on the opposite plate, said head member being insertable in the hook when assuming an angular position, but being too wide to become disengaged with the hook when turned into a vertical position. 110

2. A clasp of the character described, comprising a pair of supporting straps, a plate member secured to each strap, the lower end of each plate being turned inwardly and then upwardly to form a hook on the one plate and a head on the other, said head of the one plate being insertable into the hook of the other plate when brought to an angular position and interlocking with said hook when brought to its vertical supporting position.

3. A clasp of the character described, comprising a pair of supporting straps, a plate secured to each strap, one of said plates being greater in length than the other, and

the lower end of each plate being turned inwardly and then upwardly to form a hook on the one plate and a head on the other, said head of the one plate being insertable into the hook of the other plate when brought to an angular position and interlocking with said hook when brought to its vertical supporting position.

In testimony whereof I have hereunto set my hand in the presence of two subscribing witnesses.

WILLIAM J. DEMPSEY.
